US00D631039S

(12) United States Design Patent
Sakai et al.

(10) Patent No.: US D631,039 S
(45) Date of Patent:  Jan. 18, 2011

(54) PERSONAL COMPUTER

(75) Inventors: Sho Sakai, Kawasaki (JP); Hiroyuki Fujita, Tokyo (JP)

(73) Assignee: Fujitsu Limited, Kawasaki (JP)

() Term: 14 Years

(21) Appl. No.: 29/347,543

(22) Filed: Mar. 1, 2010

(30) Foreign Application Priority Data

Sep. 1, 2009 (JP) D2009-020068

(51) LOC (9) Cl. 14-02

(52) U.S. Cl. D14/327

(58) Field of Classification Search D14/315-327;
